UNITED STATES PATENT OFFICE.

CECIL ROBERT HOUSEMAN, OF WEMBLEY, ENGLAND, ASSIGNOR, BY MESNE ASSIGNMENTS, TO AIR REDUCTION COMPANY, INCORPORATED, A CORPORATION OF NEW YORK.

HEAT-INTERCHANGE DEVICE.

Application filed January 23, 1926, Serial No. 83,232, and in Great Britain January 28, 1925.

This invention consists in improvements in means, or apparatus, such as those described and claimed in the application of Hans Kuhni, Serial No. 600,514, filed Nov. 5 13, 1922, by which improvements the apparatus is rendered eminently adapted for use in operations requiring intimate contact between gases and liquids owing to the efficient formation of the liquid into a froth, or 10 foam, caused by the gas rising through the liquid in bubbles, or small portions of gas enveloped mostly by thin films of the liquid.

Suitable elements may be constructed as hereinafter described with reference to the 15 accompanying drawing in which:

Figure 1 illustrates, in section, an apparatus consisting of a number of elements each constructed in accordance with this invention and arranged to form a column. 20 Figure 2 is a plan of part of Figure 1. Figures 3 and 4 show, in perspective, alternative forms of thin corrugated copper ribbons hereinafter referred to and Figure 5 shows in plan, drawn to an exaggerated 25 scale, a fragment of the element, hereinafter referred to, comprising alternating corrugated and plain ribbons.

Each of the elements A shown in Figure 1 consists in, or comprises, thin copper ribbons *a* and *b* of suitable small width, one (*a*) of which is plain and the other (*b*) is corrugated transversely at a right angle as shown in Figure 3, or diagonally as shown in Figure 4. The depth of the corrugations 35 would be determined by the physical properties of the particular liquid to be operated upon, and is generally less than one-tenth of one millimetre. The said ribbons are alternatively arranged, as indicated in Figure 40 5, and are then wound spirally into the required form to constitute an element having the requisite compactness and a great number of short and minute passages up through which the gas will pass, or can be caused 45 to pass, in such manner that liquid, maintained at sufficient height upon the element, will be converted into froth, or foam, in the space above where intimate contact between the gas and liquid will be obtained, the gas

passing off, or up through another element 50 and the liquid passing down from the element to another element below through liquid sealed passages up which the gas cannot penetrate, or from the apparatus if the operation be completed. 55

The gas passages occur in the annulus which is composed of the alternate windings of the plain ribbon *a* and the corrugated ribbon *b* as shown in Figures 2 and 5. *c* indicates radial bars fixed on each side of the 60 element A for maintaining the ribbons in position between rings *d* and *e*.

The passing of the liquid from the element A, or from each of the said elements if, as will usually be the case, a number of 65 superposed elements be employed one above the other, as shown in Figure 1, is effected independently of the small spaces, or perforations, for the gas by providing each element with an overflow conduit B and seal 70 preferably arranged as indicated in Figure 1. The liquid, resulting from the condensation of the foam, or froth, and which has passed over the overflow B which determines the depth of foam, or froth, upon any particular element, flows into a well *g* having a 75 lower portion dipping into another well *h* constituting a seal up which the liquid rises and from which it passes to the next element (or into the receptacle for the treated liquid 80 if the operation be completed) by a suitable number of distributing pipes *i*. This arrangement of wells allows liquid to pass downwards, but prevents gas passing upwards along the same path when the element 85 A is functioning normally and is capable of giving great compactness in a tier of elements.

It is to be understood that the invention is not limited to the precise construction of 90 element hereinbefore described and illustrated in the accompanying drawing, as modifications may be made without departing from the scope of the invention.

What I claim is:

An apparatus for use where intimate contact between a gas and a liquid is desired, comprising a receptacle, means mounted in

said receptacle to support a body of liquid and to permit the passage of gas therethrough, said means comprising a series of alternately plain and corrugated ribbons, the 5 corrugations in said last mentioned ribbons being angularly disposed, said corrugated ribbons filling a substantial portion of the

space between the plain ribbons, whereby the plain ribbons are maintained in spaced relation and a sufficient surface is provided to maintain a liquid between said strips. 10

In testimony whereof I have signed my name to this specification.

CECIL ROBERT HOUSEMAN.
